UNITED STATES PATENT OFFICE.

CLIFFORD H. PRESCOTT, OF LAWRENCE, MASSACHUSETTS.

DRAWING-BOARD AND T-SQUARE.

SPECIFICATION forming part of Letters Patent No. 315,545, dated April 14, 1885.

Application filed December 30, 1884. (No model.)

To all whom it may concern:

Be it known that I, CLIFFORD H. PRESCOTT, a citizen of the United States, residing at Lawrence, in the county of Essex and State 5 of Massachusetts, have invented certain new and useful Improvements in Drawing-Boards and T-Squares; and I do hereby declare that the following is a full, clear, and exact description of the same, reference being had to 10 the annexed drawings, making a part of this specification, and to the letters and figures of reference marked thereon.

Figure 1 of the drawings is a perspective view of my invention; Fig. 2, an edge view 15 thereof; and Fig. 3, a detail view of the head of the T-square and guide-rod, showing them connected together.

The present invention has relation to that 20 class of combined T-squares and drawing-boards in which the head of the square is connected to the board and adapted to slide along the edge thereof, and is especially designed as an improvement on my former patent, No. 25 308,040, dated November 11, 1884; and it consists in the details of construction substantially as shown in the drawings, and herein-after described and claimed.

In the accompanying drawings, A represents the drawing-board, and B the T-square, 30 the head *a* thereof having connected to its inner edge a metal saddle, C. In the present instance I have shown the head *a* formed of wood, and the saddle constructed of metal consisting of a rectangular strip provided at 35 its extremities with notched projections *b*, and midway of its ends an eye, *c*, through which the guide-rod D passes, the rod fitting in the notched extremities or projections *b*.

Should it be considered preferable to form 40 the head *a* of metal, the notched projections and eye may be cast with it.

The rod D fits in a grooved metallic strip, E, 45 suitably connected to one edge of the board A; but, if preferred, the groove may be made in the edge of the board, which would serve the same purpose, but not as well. The rod D has one of its ends bent at right angles to 50 form a slotted extension, *d'*, the opposite extension, *d*, being made separate and afterward secured to the end of the rod in any suitable

manner. By means of these slotted extensions the rod is held within the groove at the edge of the board by screws *e*, the elongated slots in the extensions admitting the adjustment of the rod within the groove and held 55 in its adjusted position by the set-screws, thus enabling the head of the T-square to slide with greater or less friction upon the grooved edge of the drawing-board.

The above-described means is a very simple 60 and effective way to hold the T-square head against the edge of the drawing-board and admit it sliding as required.

Having now fully described my invention, what I claim as new, and desire to secure by 65 Letters Patent, is—

1. The combination, with a drawing-board having a groove in one of its edges and a guide-rod located therein, of a T-square connected to the rod and adapted to slide thereon, substantially as and for the purpose set forth. 70

2. The combination, with a drawing-board having a groove in one of its edges and a guide-rod adjustable therein, of a T-square 75 connected to said rod and adapted to slide thereon, substantially as and for the purpose specified.

3. The combination, with a drawing-board having a groove in one of its edges and a guide-rod terminating at its ends in angular slotted extensions and held within the groove by set-screws entering the slots of said extensions, of a T-square connected to the rod and adapted to slide thereon, substantially as and for the purpose described. 80

4. A drawing-board having in one of its edges a groove and a guide-rod, in combination with the head of a T-square provided with a saddle consisting of notched projections, and an eye for connecting the head to the rod, substantially as and for the purpose set forth. 85

In testimony that I claim the above I have hereunto subscribed my name in the presence 90 of two witnesses.

CLIFFORD H. PRESCOTT.
